CHILD'S PLAY MAT

Robert L. Mitchell, Los Angeles, Calif.

Application April 14, 1952, Serial No. 19,312

Term of patent 7 years

(Cl. D9—6)

To all whom it may concern:

Be it known that I, Robert L. Mitchell, a citizen of the United States of America, residing in the city of Los Angeles, in the county of Los Angeles, State of California, have invented a new, original, and ornamental Design for a Child's Play Mat, of which the following is a specification, reference being had to the accompanying drawing, forming a part thereof.

Fig. 1 is a plan view of a child's play mat showing my new design; and

Fig. 2 is an enlarged partial cross sectional view taken along the line 2—2 of Fig. 1.

I claim:

The ornamental design for a child's play mat, substantially as shown.

ROBERT L. MITCHELL.
